UNITED STATES PATENT OFFICE.

LOUIS BABINI, OF BROOKLYN, NEW YORK, ASSIGNEE TO AMERICAN ADDING MACHINE CORPORATION, A CORPORATION OF NEW YORK.

ADDING-MACHINE.

1,108,115.

Specification of Letters Patent. Patented Aug. 25, 1914.

Application filed July 14, 1911. Serial No. 638,595.

To all whom it may concern:

Be it known that I, LOUIS BABINI, a citizen of the United States, residing at Brooklyn, in the county of Kings and State of New York, have invented certain new and useful Improvements in Adding-Machines, of which the following is a full, clear, and exact description, reference being had to the accompanying drawings, forming a part of this specification.

This invention relates to adding machines, and more particularly to that class of adding machines having a writing attachment operated simultaneously with the adding mechanism by the action of the same levers, and its principal object is to provide an adding machine of a simple design and substantial construction, adapted to be manufactured and sold at a low figure, and to perform in a reliable way all the services usually required of an adding machine.

A further object of this invention is to provide a novel and simplified mechanism for printing the different figures in a proper order on a strip of paper, while at the same time said figures are automatically added by the adding or registering mechanism.

With these and other objects in view, as will more fully appear as the description proceeds, this invention consists in certain constructions and arrangements of parts as will be hereinafter described and claimed in the appended claims.

Referring to the drawings, Figure 1 is a side sectional view in elevation of my improved machine, showing the operation of the adding mechanism; Fig. 2 is a side view in elevation of the same, with some parts of the printing mechanism removed, and some sectioned; Fig. 3 is a side view in elevation of the machine, showing all parts of the printing mechanism in place; Fig. 4 is a detail plan view of certain parts of the printing mechanism; Fig. 5 is a detail view on an enlarged scale, and sectioned, of an arrangement for setting all the counting wheels at the starting point; Fig. 6 is a rear view in elevation, partly broken away, of the machine; Fig. 7 is a front view in elevation of the same; and Fig. 8 is a plan view of the same.

My improved machine consists essentially

of three parts; one stationary, or body proper of the machine, embodying the operating parts; one movable, or carriage, in which is mounted the adding mechanism; and a device attached to the side of the body, for printing on a strip of paper the different addenda, which are at the same time summed up in a general total by the adding mechanism. The stationary part comprises a case 1, provided with a fulcrum rod 2, on which are loosely mounted nine levers 3, and provided with a fulcrum rod 5 on which are loosely mounted two levers 6, 7. Levers 3 are provided with touches 4 numbered from 1 to 9, and levers 6, 7, are provided with touches 4', corresponding respectively to the numeral 0 and to the spacing device for allowing the escapement of the carriage of one column space to the left. A rod 8 acts as a fulcrum for nine geared segments 9, connected by links 10 to levers 3, and operated by the same; springs 11, attached to a rod 12, oppose the depressing of levers 3, and will return the same to their original position, shown in the drawings (Fig. 1). On the fulcrum 8 are also mounted, one at each side of case 1, and internally to the same, two crank levers having an upper arm 13 and a lower arm 14. The two arms 13 are connected by a rib 15, and the two arms 14 are connected by a rib 16. The lever 6 has its free end abutting against the lower side of said rib 16, as shown in Fig. 1.

A geared drum 18 is mounted on a shaft 19 running the entire length of case 1, and projecting outside at the left side of the same; and said drum 18 is adapted to come in mesh with any of the segments 9, upon these being operated by the corresponding levers 3. Said segments 9 have a portion 9' provided with teeth, and a toothless portion 9'', which in position of rest, as shown in Fig. 1, is opposite geared drum 18, allowing the free movement of the same. A toothed wheel 20, from which a portion of its teeth have been removed, and which in the preferred embodiment of my invention is shown as having twelve teeth with two teeth missing, is fixed on drum 18 in such a manner that in the position of rest, the free space left by the missing teeth will clear the train of adding wheels 21, which is

mounted on a shaft 22 in carriage 23, thereby permitting the free longitudinal motion of said carriage.

24 is a lever loosely mounted on a pivot 5 25 on the right or on the left side of case 1, and is provided with two notches, 26, 27, a finger 28 at one end, and a stop 29 abutting against the inside surface of case 1, at the other. Drum 18 is also provided with a 10 finger 30. In the position shown in the drawings, notch 26 engages rib 15 connecting arms 13 (Fig. 1).

Upon one of the levers 3 being depressed with the finger, the corresponding link 10 15 will pull arm 31 of the corresponding geared segment 9, causing the same to revolve around its fulcrum 8 and to come in mesh with drum 18, rotating the same an angle proportional to the number of teeth in 20 the segment which have come in mesh. At the end of the stroke, free end 32 of the segment, will strike against rib 15, swinging arms 13 toward the rear, until lever 24 will fall on account of its weight, and notch 27 25 engage rib 15, preventing the same from going back to its previous position. Upon releasing the lever 3, spring 11 will return it to its former position, causing a reverse movement of segment 9 and drum 18 to take 30 place. At the end of this return stroke, finger 30 of drum 18 striking against finger 28 of lever 24, will swing said lever so that rib 15 will be disengaged, and the weight of arms 14 will cause arms 13 to return to the 35 position shown in the drawings, rib 15 engaging again notch 26.

The carriage, 23, is slidably mounted on a rod 33, attached to the rear part of case 1 by means of upright 34. Said carriage is 40 pulled toward the left side of the machine by a tape 35, attached to its bottom, and winding itself upon a drum of a spring motor of ordinary design, 36. The motion of the carriage is controlled by a rack 37 swinging 45 on a shaft 38, said rack being normally held in its forward position shown in the drawings, against stop 39, by the action of a spring 40 pulling its arm 41, or in any other suitable manner (Fig. 1). Said rack 50 37 is provided with a number of teeth 42, one of which is normally abutting against a stop 43 projecting through the bottom of the carriage. Another stop 44 projects through the same, at the rear of stop 43, and at its 55 left side, looking from the rear of the machine, as in Fig. 6. In this same figure, between the two stops, is seen a free space 45, sufficient for the passage of one tooth 42 of the rack. Said stops 43, 44, (Fig. 1) are 60 not fixed to the bottom of the carriage, but are attached to a spring 46 internally fixed to the same, and project through its bottom. Said spring 46 is attached in 47 to the front of the carriage 48, so that a pressure direct-

ed upward against the lower face of stops 65 43, 44, will raise the same against the action of said spring. Rack 37 is provided with 70 housings 49, through which project arms 52 of lever 50. This is a part of a column selecting device which may be built in connection with my machine, the other parts of which consist of a stop 53 fixed to the bottom of the carriage, and by a number of rods 54 mounted in bearings 55, 56, in correspondence with the different lever arms 52. 75 Said rods 54 project outside on the front of the machine, and are provided with touches 57. The same are operated with the fingers, and upon being released, springs 58 will return them to the position shown in the 80 drawing, until stops 59 will abut against the inside of case 1 (Fig. 1). Rack 37 is also provided with an arm 60, projecting above rib 16.

Each counting wheel 21 consists of a drum 85 21' in which are marked the numerals from 0 to 9; of a toothed part 21'', adapted to come in mesh with toothed wheel 20; and of a hub 21''' of a smaller diameter, clearing the outside diameter of wheel 20, and causing a gap 61 to be formed between one part 21'' and one part 21' of the next counting wheel. One toothed part 21'' is normally in front of wheel 20, so that upon this being revolved, it will drive part 21'' and corresponding drum 21' for an angle corresponding to the number of teeth of the segment causing the rotation of drum 18 and wheel 20 (Figs. 1, 5, 7).

The operation of these different parts is as 100 follows: Upon one of the levers 3 being depressed, the corresponding segment 9 is swung around its fulcrum 8 in the manner described, causing the rotation of drum 18, and wheel 20, a number of teeth proportional 105 to the number of teeth in the segment coming in mesh with said drum. Wheel 20 will in its turn cause the rotation of the wheel 21'' and corresponding numbered drum 21', a number of teeth in the same proportion. 110 When the segment 9 has arrived at the end of its stroke, it will strike rib 15, pushing the same backward, until the same engages notch 27. Arms 14, and their connecting rib 16 will consequently be lifted during the 115 movement of part 15, so that rib 16 striking against arm 60 of rack 37 will cause the same to swing back releasing stop 43. The action of the spring motor then pulls the carriage toward the left, until stop 44 strikes 120 against the tooth 42 formerly engaged with 43. This first half-stroke of the carriage is such that the wheel 21'' formerly in mesh with 20 has been displaced enough to have the corresponding hub 21''' opposite to 125 wheel 20, so that this is now free to move without causing any movement in the counting wheels. Upon releasing the lever 3, seg-

ment 9, and drum 18 with wheel 20 return to their former positions, at the end of this return stroke finger 30 striking finger 28, releasing part 15 and consequently allowing arms 14 and connecting rib 16 to drop back in their former position. Spring 40 will cause the return forward of rack 37, thus freeing stop 44, the tooth 42 of the rack engaged by the same passing through the free space 45. The carriage is then free to complete its stroke, until the next tooth 42 of the rack will be in the way of stop 43. At this stage the carriage is stopped, and a new wheel 21" is in front of wheel 20 for the next numeral to be inserted. By depressing the lever 6, corresponding to the numeral 0, its end 17 strikes against 16 causing the back movement of 15, and operating the rack in the manner described, the carriage being moved one space to the left. During this backward movement of part 15, lever 24 will not fall on account of its weight, inasmuch as its finger 28 is engaged and retained by finger 30 of drum 18; part 15 is therefore free to return to its normal position when lever 6 is released. Spacing lever 7 only operates against arm 60, causing the swinging of the rack 37 and the motion of the carriage also of one space to the left. When the carriage has to be moved for more than one space, it being necessary to start the insertion of a new addendum from a given column, the corresponding rod 54 is depressed. The same will raise the corresponding cam-shaped arm 52 of lever 50, which in its turn will raise stops 43, 44, freeing the carriage 23 from the rack. The same is then free to move toward the left until stop 53 strikes against the rod 54 which is depressed. Upon releasing this lever 50 and stops 43, 44 are again lowered by the action of spring 46 so that the carriage will not move farther. The insertion of the new addendum is then started and completed.

To avoid the complication of an auxiliary shaft and gears, used in many adding mechanisms for causing the motion of the next higher wheel of one space when the number ten is passed in any given wheel, I have devised a novel and simple arrangement for the relative motion of the different counting wheels, which I shall now describe.

Each hub 21" is provided with a finger 62, which in its rotation will clear the wheel 61 which might be in the corresponding gap 61; said gap 61 being sufficiently wide for the passage of both wheel 20 and finger 62 at the same time. Into each gap 61, at the rear of the hubs 21", is located a lever 63 loosely mounted on a fulcrum 64. Said lever is held in the position shown in the drawings (Fig. 1) by the action of a spring 65, and is provided with a projection 66, coming out of an opening 67 provided at the rear part

of the carriage. Arm 68 of lever 63, against which is pressing spring 65, is of such a shape that said spring can hold the lever in two different positions, which can be called the raised and lowered positions, the position shown in the drawing being the raised (Fig. 1). A pawl 69, engaging the toothed wheel 21" on the left of each lever 63, is loosely mounted on pin 70, attached to said lever, and has two arms; one 69' engages the toothed wheel, and the other, 69", is bent downward, and is used to disengage arm 69' by operating a rod 71 at the rear, as will be at a later stage described. The carriage is provided with windows 72, through which the different numbers appear; and the position of finger 62 shown in the drawing corresponds to the figure 9 appearing through the corresponding window 72. Upon the counting wheel being rotated, finger 62 will push lever 63 in its lowered position, where it will be held by spring 65; arm 69' of pawl 69 will have thus engaged another tooth of the next higher counting wheel.

73 is an inclined plane attached to the back of the case 1, against which projections 66 of the levers 63 which happen to be in the lowered position strike when the carriage is returned to its starting position. The action of said inclined plane is to return such levers to the raised position, pawls 69 causing the corresponding wheels 21" to advance one space forward, and thus effecting the addition of ten units due to the next wheel to the right having passed the zero point and having at that time lowered the corresponding lever 63.

A spring 73', or any other suitable means, is used to exert a braking action against any undue motion of the counting wheels (Fig. 1).

71 is a C shaped rod or yoke having its fulcrum in 74, operated by a lever 75, normally held by a spring 76 against a stop 77 (Figs. 1 and 2). By swinging said lever forward, rod 71 disengages all the pawls 69; this is done in two instances. When it is desired to correct the reading of one of the counting wheels, the same is revolved by hand through its corresponding window 72; if it should happen in so doing to cause the lowering of the corresponding lever 63, before raising the same by means of the projection 66, the rod 71 is pushed against the pawls 69 by means of lever 75; the lever which has been lowered is raised, lever 75 released, and all the pawls 69 will fall back in the same place occupied before (Figs. 1 and 2). Lever 75 is also used when it is necessary to return all the counting wheels to the 0 mark. To this effect shaft 22 is made longitudinally movable by means of a button 78, against the action of a coil spring 79; said spring has one end fixed to a point

80 of the case, and also opposes the circular motion of shaft 22 (Fig. 5). Said shaft 22 is provided with projections 81, which normally do not interfere with the motion of the 5 counting wheels, these being provided with chambers or housings 82 accommodating said projections; but when shaft 22 is pulled to the right, said projections 81 will engage noses 83 of which there is one in each counting wheel, and drive said counting wheels to the 0 mark upon the rotation of shaft 22. To do this, pawls 69 are previously raised and disengaged from the counting wheels, by means of lever 75, in the manner explained. Shaft 22 is kept in its normal position by means of a pin 84 engaging a hole in the side of the case 1.

The machine is fitted with a device for printing the different addenda on a strip of 20 paper, which consists of a printing wheel, a paper feed, and an inking ribbon.

On the portion of shaft 19 projecting outside of case 1, is mounted a pinion 85, in constant mesh with a geared segment 86 25 (Figs. 2 and 4). 87 is a spring opposing the motion of said segment and pinion due to levers 3. 88 is a stop acting against stop pin 89 to stop the backward motion of shaft 19 due to spring 87. Toward the front of the 30 machine a pinion 90, similar to pinion 85, is mounted on a shaft 91, in mesh with segment 86; said segment 86 is free to swing around its fulcrum 92. On shaft 91 is mounted a sleeve 93, having at one end a 35 toothed wheel 94, and at the other a printing wheel 95 carrying the types of numerals 0 to 9. A spring 96, or any other suitable means establishes an elastic connection between shaft 91 and sleeve 93, so that shaft 40 91 drives sleeve 93, but when this should be stopped, shaft 91 can continue its motion until a pin 97 strikes the wall of a transverse opening 98 provided in sleeve 93. The numeral 0 is normally toward the rear of 45 the machine.

99 is the hammer, connected by means of screws 100 or otherwise, to part 15 (Fig. 6).

101 is a bracket attached to the side of the case, bearing guide rolls 102, 103, 104, 50 for the inking ribbon 105. Roll 104 is fitted with a toothed wheel 106, the backward motion of which is prevented by a spring 107.

108 is an inking drum for keeping the inking ribbon in the proper condition (Fig. 3).

On a bridge 109, attached to case 1 by means of screws 110, or in any other suitable manner; are mounted two guide rods 111, 112, on which longitudinally slides a box 60 or frame 113 containing a paper roll 114 (Figs. 2, 3). The paper strip, 115, is fed through a slot 116 to the upper part of the box, underneath a roll 117, against which it is held by a spring 118, and out, between

hammer 99 and inking ribbon 105. Roll 65 117 is mounted on a sleeve 119, loosely revolving around guide rod 112, and provided at its inner end, with a face toothed wheel 120. A pawl 121 is pivoted on bridge 109, and forced outward by a spring 122. If box 70 113 is pulled toward case 1, and against pawl 121, this is forced inward, causing face toothed wheel 120 which it engages, to revolve, driving roll 117, and feeding the paper strip for a space between addenda 75 (Figs. 2, 4). Box 113 is movable longitudinally in order to print the numerals in the different columns, and is driven in this motion by carriage 23. To this effect, carriage 23 is fitted with a toothed rack 123, in mesh 80 with a gear 124 revolving on a stud 125 attached to the case. To said gear is attached a pinion 126, driving a rack 127, connected in 128 to box 113. In this manner, the successive steps in the motion of carriage 23 85 are transmitted in a reduced length to box 113, a new space being offered for the printing of a numeral at each step (Fig. 8).

The printing mechanism operates as follows: Upon one of the levers 3 being depressed, while the corresponding figure is added to the counting wheel 21 in mesh with 90 20, the motion of drum 18 is also transmitted by pinion 85 to segment 86 and to pinion 90. This causes printing wheel 95 to 95 rotate presenting the numeral corresponding to the depressed lever to the action of the hammer 99. When rib 15 is pushed backward, at the end of the stroke of the lever, hammer 99, carried thereby, will strike 100 against printing wheel 95; the inking ribbon and the strip of paper being in between, the numeral will remain printed on the latter. To insure a clear printing, hammer 99 has a pawl 129 which will engage toothed 105 wheel 94 thus locking the printing wheel in the right position, at the end of the stroke. Upon releasing the lever 3, the hammer 99 and the printing wheel 95 will return to their former positions, and box 113 will 110 move one space to the left. Hammer 99 is also provided with a spring 130, engaging toothed wheel 106, and driving the same one space upon the return stroke of the hammer. Said return stroke of the hammer is 115 effected as stated by the weight arm 14, which controls part 15 to which hammer 99 is attached; and it is of course understood that said arm 14 will have to be made sufficiently heavy to perform the return motion 120 of the hammer, at the same time driving toothed wheel 106. In this way roll 104 is 125 revolved at every insertion, providing a simple and efficient feed for the inking ribbon. When an addendum has been totally inserted, the carriage 23 is returned to its initial point, to start the insertion of a new addendum. This motion is followed by box

113, which will thus be brought against pawl 121; this will cause wheel 120 to rotate of one space, thus feeding the strip of paper accordingly, and offering a new space to the 5 action of the printing wheel.

From the foregoing it will be seen that I provide a novel disposition for imparting the motion to the different counting wheels, simple in design and inexpensive to manufacture; also an improved way of imparting a partial rotation to the wheels of higher denomination, upon the completion of one rotation of the next wheels of smaller denomination. It will also be noted that I 10 provide a most simple disposition for driving a printing wheel instead of the type levers usually adopted in this kind of machines.

It is obvious that while the different numbers of teeth indicated by me for the various moving parts are those that most conveniently answer the purpose of my machine, they can be varied provided the relative proportions are maintained; it is 25 also obvious that in the printing arrangement the record strip can be made stationary and the printing wheel may be made longitudinally movable. These and other changes can be made in the specific details of 30 construction of my machine, without departing from the spirit of my invention; therefore I do not wish to be restricted to those shown and described.

Having thus described my invention, what 35 I claim as new, and desire to secure by Letters Patent of the United States, is:

1. The combination of a plurality of adding wheels, a carriage carrying the same, a geared longitudinally extending element, a 40 toothed wheel having a portion of its teeth removed mounted on the same, and means for revolving said longitudinally extending element at different angles.

2. The combination of a plurality of 45 geared adding wheels, a carriage carrying the same, elements of a smaller diameter leaving a free gap between adjacent wheels, a rack controlling the motion of said carriage, a longitudinally extending element, a 50 toothed wheel mounted on the same adapted to come in mesh with said adding wheels, geared means for revolving said longitudinally extending element at different angles, finger-keys controlling the same, and means 55 for causing said rack to disengage said carriage allowing the same to move for a portion of its stroke upon the pressing of said finger-keys, and for causing said rack to return to its former position permitting the 60 completion of the stroke of said carriage upon the releasing of said finger-keys.

3. The combination of a plurality of 65 geared adding wheels, a carriage carrying the same, elements of a smaller diameter

separating adjacent wheels, a rack controlling the motion of said carriage, a toothed wheel adapted to come in mesh with said adding wheels, a rocking element controlling the motion of said rack, means for locking said rocking element in two different positions, and finger-key operated means for governing said toothed wheel and said rocking element. 70

4. The combination of a plurality of geared adding wheels, a carriage carrying the same, elements of a smaller diameter separating adjacent wheels leaving a free gap between the same, a rack controlling the motion of said carriage, a toothed wheel from which a portion of its teeth has been removed adapted to come in mesh with said adding wheels, geared means for revolving said toothed wheel and means for operating the same and for operating said rack, causing a two-step escapement of said carriage. 80

5. The combination of a plurality of geared adding wheels, a carriage carrying the same, elements of a smaller diameter separating adjacent wheels, a rack controlling the motion of said carriage, a longitudinally extending element, a toothed wheel from which a portion of its teeth has been removed mounted on the same, a plurality of geared segments capable of revolving said longitudinally extending element at different 95 angles, levers controlling said segments, a rocking element controlling the motion of said rack operated by said segments and levers, and means for locking said rocking element at different points. 100

6. The combination of a plurality of geared adding wheels, a carriage carrying the same, elements of a smaller diameter separating adjacent wheels, a rack controlling the motion of said carriage, a longitudinally extending element, a toothed wheel from which a portion of its teeth has been removed, adapted to come in mesh with said adding wheels mounted on the same, a plurality of geared segments capable of revolving said longitudinally extending element at different angles, levers controlling said segments, a rocking element controlling the motion of said rack, operated by said segments and levers; means for locking said 115 rocking element in two different positions, and means for controlling the action of said locking element.

7. The combination, with a longitudinally moving carriage, of a plurality of geared adding wheels separated by an element of a smaller diameter leaving a gap between said wheels, levers through said gaps having a nose projecting outside of said carriage and carrying a pawl engaging the wheels of the 120 higher denomination, means connected with the wheels of smaller denomination for pushing said levers outward upon the passing

- ing of ten unities on said wheels; means for holding said levers in the two mentioned positions, and a stationary inclined plane causing the return of said levers to their former positions driving the counting wheel engaged of one space forward, upon the return stroke of said carriage.
8. The combination, with a longitudinally moving carriage, of a plurality of geared adding wheel separated by an element of a smaller diameter leaving a gap between said wheels, revolubly mounted on a stationary shaft, levers through said gaps having a nose projecting outside of said carriage and carrying a pawl engaging the wheels of the higher denominations, means connected to the wheels of smaller denomination for pushing said levers outward upon the passing of ten unities on said wheels, springs holding said levers in the two mentioned positions, a stationary inclined plane against which said projecting noses slide upon the return travel of said carriage causing said levers to return to their former positions driving the counting wheels engaged of one space forward, hand operated means for simultaneously disengaging all the pawls from said wheels, and means for longitudinally and revolubly operating said stationary shaft causing the return of all counting wheels to the stationary point.
9. The combination of a longitudinally moving carriage, an adding mechanism carried thereby, a lever operated revolving element controlling said mechanism, a printing wheel carrying numeral types from 0 to 9, means for transmitting the circular motion of said element to said printing wheel, a record strip, an inking ribbon, means for pressing said inking ribbon and record strip against said printing wheel, and means controlled by said carriage for causing the printing to take place in succession upon said record strip, and according to the operation of said adding mechanism.
10. The combination of a longitudinally moving carriage, an adding mechanism carried thereby, a lever operated revolving element controlling said mechanism, a printing wheel carrying numeral type from 0 to 9, means for transmitting the circular motion of said element to said printing wheel, an inking ribbon, a record strip, a longitudinally slidble box carrying said record strip, driven by said carriage, means for feeding said strip, and means for pressing said record strip and inking ribbon against said printing wheel.
11. The combination of a longitudinally moving carriage, an adding mechanism carried thereby, a lever operated revolving element controlling said mechanism, a printing wheel carrying numeral types from 0 to 9, means for transmitting the circular motion of said element to said printing wheel, an inking ribbon, a record strip, a longitudinally slidble box carrying said record strip, driven by said carriage, means for feeding said strip, and means for pressing said record strip and inking ribbon against said printing wheel.
12. The combination of a longitudinally moving carriage, an adding mechanism carried thereby, a printing wheel, a record strip, a longitudinally movable element carrying the same, a rack attached to said carriage, a rack attached to said strip carrying element, and means for transmitting the motion of the former to the latter at a reduced ratio.
13. The combination of a longitudinally moving carriage, a plurality of adding wheels carried thereby, members adapted to engage said adding wheels, means for causing said members to assume an operative position for imparting a partial rotation to a wheel upon the completion of one rotation of the next wheel of smaller denomination, and cam-acting stationary means operating said members causing said partial rotation, upon the return travel of said carriage.
14. The combination of a stationary part, a carriage longitudinally movable thereon, an adding mechanism carried by said carriage, a rotatable element controlling said adding mechanism, finger-key operated geared means controlling the angle of rotation of said element, a rack controlling the escapement of said carriage, a rocking element governing said rack, a printing wheel carrying the numeral types from 0 to 9, means for transmitting the motion of said rotatable element to said printing wheel, a record strip, and means for causing said printing wheel to print on said strip.
15. The combination of a rotatable element, a printing wheel, means for transmitting the motion of the former to the latter, a shaft, elastic connections between said printing wheel and shaft, and means for stopping the motion of said printing wheel, while said shaft completes its rotation.
16. The combination of a stationary part, a carriage longitudinally movable thereon, an adding mechanism carried by said carriage, a rotatable element controlling said adding mechanism, finger-key operated means controlling the angle of rotation of said element, means for controlling the escapement of said carriage, printing devices co-operating with said rotatable element and actuated thereby, and column selective devices for determining the relative adjustment of said adding mechanism and said rotatable element.
17. The combination of a stationary part,

5 a carriage longitudinally movable thereon, an adding mechanism carried by said carriage, a motor wheel, finger-key operated geared means controlling the angle of rotation of said wheel, means for causing a two-step escapement of said carriage, a printing wheel, means for revolving said printing wheel simultaneously with and proportionally to said motor wheel, and means for 10 printing the different numerals as they are registered by said adding mechanism, and in the same relative order.

18. The combination of a stationary part, a carriage longitudinally movable thereon, 15 an adding mechanism carried by said carriage, a motor wheel, a printing wheel, a rotatable element controlling the relative motion of said wheels, rocking means controlling the escapement of said carriage, and 20 finger-key operated segments governing said rotatable element and rocking means.

19. The combination of a stationary part, a carriage longitudinally movable thereon, an adding mechanism carried by said carriage, a motor wheel, a printing wheel, a rotatable element controlling the relative motion of said wheels, rocking means controlling the escapement of said carriage, finger-key operated segments governing said 30 rotatable element and rocking means, and column selective devices for determining the relative adjustment of said adding mechanism and said motor wheel.

20. The combination of a stationary part, 35 a carriage longitudinally movable thereon, an adding mechanism carried by said carriage, a rotatable element, a motor wheel mounted thereon, a rack, rocking elements controlling the motion of said rack so as to cause a two step escapement of said carriage, finger-key operated geared segments governing said rotatable element and rocking means, a printing wheel, means for transmitting the motion of said rotatable element 45 to said printing wheel, a record strip, means controlled by said carriage for feeding the same, and means connected to said rocking means for causing said printing wheel to print on said record strip.

21. The combination of a stationary part, a carriage longitudinally movable thereon, 50 an adding mechanism carried by said carriage, a rotatable element, a motor wheel mounted thereon, a rack, rocking elements controlling the motion of said rack so as to cause a two step escapement of said carriage, finger-key operated geared segments governing said rotatable element and rocking means, a shaft, a printing wheel mounted 55 thereon, elastic connections between said shaft and printing wheel, geared means for transmitting the motion of said rotatable element to said shaft, a record strip, a carrier for the same driven by said carriage, 60 means for feeding said record strip, an ink- 65

ing ribbon, and means connected to said rocking means for causing said printing wheel to print on said record strip.

22. The combination of a stationary part, a carriage longitudinally movable thereon, 70 an adding mechanism carried by said carriage, a rotatable element, a motor wheel mounted thereon, a rack, rocking elements controlling the motion of said rack so as to cause a two step escapement of said carriage, 75 finger-key operated geared segments governing said rotatable element and rocking means, a shaft, a printing wheel mounted thereon, elastic connections between said shaft and printing wheel, geared means for 80 transmitting the motion of said rotatable element to said shaft, a record strip, means controlled by said carriage for feeding the same, means connected to said rocking means for causing said printing wheel to print on 85 said record strip, and column selective devices for determining the relative adjustment of said adding mechanism and said motor wheel.

23. The combination of an adding mechanism comprising a plurality of adding wheels, a movable carriage carrying the same, a toothed wheel having a portion of its teeth removed successively engaging into mesh with said adding wheels and controlling 90 the same, means for revolving said wheels at different angles, and means for moving said carriage.

24. The combination of an adding mechanism comprising a plurality of adding 100 wheels, a movable carriage carrying the same, a toothed wheel, having a portion of its teeth removed, successively engaging directly into mesh with said adding wheels and controlling the same, geared means for 105 revolving said wheels at different angles and means for moving said carriage.

25. The combination of a plurality of adding wheels, a carriage carrying the same, a toothed wheel successively engaging into 110 mesh with said adding wheels and controlling the same, and finger-key actuated means operating said toothed wheel and the escapement of said carriage.

26. The combination of a plurality of adding wheels, a carriage carrying the same, a toothed wheel successively engaging into mesh with said adding wheels, means for 115 revolving said wheel at different angles, and means actuated thereby controlling the escapement of said carriage.

27. The combination of a plurality of adding wheels separated by free gaps between adjacent wheels, a carriage carrying the same, a toothed wheel with a portion of its teeth removed successively engaging into mesh with said adding wheels and controlling the same, a two-step escapement for 125 said carriage, and finger-key operated means revolving said wheel at different angles and 130

controlling said escapement; for the purposes as set forth.

28. The combination of a plurality of adding wheels, a carriage carrying the same, a 5 geared longitudinally extending element, a toothed wheel fixed on the same successively engaging into mesh with said adding wheels, a plurality of geared segments adapted to

come in mesh with said longitudinally extending element, and finger-keys operating 10 said segments.

LOUIS BABINI.
